[57] **CLAIM**

The ornamental design for a shoe sole, as shown and described.

DESCRIPTION

FIG. 1 is a top view of the shoe sole, showing my new design;

FIG. 2 is a side view thereof;

FIG. 3 is a bottom view thereof;

FIG. 4 is the other side view thereof;

FIG. 5 is a front view thereof, and,

FIG. 6 is a rear view thereof.

The broken line showing of the shoe upper in FIG. 2 is for illustrative purposes only and forms no part of the claimed design.
